By his Attorneys,
Baldwin Wright

UNITED STATES PATENT OFFICE.

JOHN HERBERT MANSELL, OF COVENTRY, ENGLAND, ASSIGNOR TO THE COVENTRY
ORDNANCE WORKS, LIMITED, OF COVENTRY, ENGLAND.

FUSE FOR PROJECTILES.

1,298,076.

Specification of Letters Patent. Patented Mar. 25, 1919.

Application filed July 1, 1918. Serial No. 242,847.

To all whom it may concern:

Be it known that I, JOHN HERBERT MANSELL, a subject of the King of Great Britain, residing at Ordnance Works, Coventry, 5 England, have invented a new and useful Improvement in Fuses for Projectiles, of which the following is a specification.

This invention relates to improvements in fuses for high explosive shells, its object being to provide a fuse which shall produce a powerful detonation so as to detonate with 10 certainty the charge of the shell and shall also be safe to handle.

In the accompanying drawings:—

15 Figure 1 is a longitudinal section partly in elevation of a fuse embodying my improvements.

Fig. 2 is a similar view of a modification.

Referring to Fig. 1, *a* is the body of the 20 fuse into which screws a steel gaine *b*, and a diaphragm *c* is screwed into the gaine *b*. In front of the diaphragm *c* is a charge *d* of high explosive, such as trinitrophenyl-methylnitramin or tetryl, in the middle of 25 which is powder *e* insulated from the charge *d* by a paper cylinder *f* at the ends of which are insulating paper cups *g* and *h*. Behind the diaphragm *c* is a larger charge 30 of high explosive, such as tetryl, and between the charge *d* and the diaphragm *c* is a powder pellet *j*.

The fuse shown in Fig. 2 is similar to that shown in Fig. 1 except that the powder pellet *j* is smaller and another powder pellet *k* 35 is placed in front of the charge *d*.

When the flash from either the time or percussion arrangement reaches the powder pellets *k*, the latter is ignited and the powder *e* and the high explosive *d* are in turn 40 ignited which in turn ignite the powder pellets *j* which are interposed between the inner ends of the charges *d* and *e* and the dia-phragm *c*. The ignition of the charges above referred to causes the diaphragm *c* to be broken or perforated and the high explosive in rear of the diaphragm is then 45 ignited. By thus arranging the powder pellets in connection with the other charges mentioned, the detonation of the major

charge is made more complete and certain 50 than in arrangements hereinbefore employed.

What I claim is:—

1. In a shell fuse, the combination of a gaine, a solid transverse diaphragm therein, 55 a charge of high explosive in front of the diaphragm, another charge of high explosive in rear of the diaphragm, and a powder pellet between the two charges.

2. In a shell fuse, the combination of a 60 gaine, a solid transverse diaphragm therein, a charge of high explosive in front of the diaphragm, another charge of high explosive in rear of the diaphragm, a powder pellet between the two charges and powder in the 65 interior of and insulated from the first charge.

3. In a shell fuse, the combination of a gaine, a solid transverse diaphragm therein, 70 a charge of high explosive in front of the diaphragm, another charge of high explosive in rear of the diaphragm and a powder pellet at each end of the first charge of high explosive.

4. In a shell fuse, the combination of a 75 gaine, a solid transverse diaphragm therein, a charge of high explosive in front of the diaphragm, another charge of high explosive in rear of the diaphragm, a powder pellet at each end of the first charge of high explosive, and powder in the interior of and insulated from the first charge of high explosive. 80

5. In a shell fuse, the combination of a gaine, a solid transverse diaphragm therein, 85 a charge of high explosive in front of the diaphragm, another charge of high explosive in rear of the diaphragm, and a powder pellet interposed between the ends of the two charges. 90

6. In a shell fuse, the combination of a gaine, a solid transverse diaphragm therein, a charge of high explosive in front of the diaphragm, another charge of high explosive in rear of the diaphragm, and a powder pellet interposed between the diaphragm and the inner end of the high explosive charge 95 in front of said diaphragm.

7. In a shell fuse, the combination of a
gaine, a solid transverse diaphragm therein,
a charge of high explosive in front of the
diaphragm, another charge of high explosive
5 in rear of the diaphragm, a powder pellet
interposed between the ends of the two
charges and a mass of powder arranged in

the interior of and insulated from the first
charge.

In testimony that I claim the foregoing as 10
my invention, I have signed my name this
31st day of May, 1918.

JOHN HERBERT MANSELL.
